CLAIM

The ornamental design for a portable two-way radio, as shown and described.

DESCRIPTION

FIG. 1 is a top, front and left side perspective view of a portable two-way radio showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a bottom plan view thereof;

FIG. 8 is a top, front and left side perspective view of a second embodiment of the portable two-way radio illustrated in FIG. 1; and

FIG. 9 is a front elevational view of the embodiment disclosed in FIG. 8.

The broken line showing of the antenna is for illustrative purposes only and forms no part of the claimed design.
